UNITED STATES PATENT OFFICE.

WILLIAM J. KLAUBERG, OF NEW YORK, N. Y.; CHARLES J. KLAUBERG AND WILLIAM W. KLAUBERG, EXECUTORS OF SAID WILLIAM J. KLAUBERG, DECEASED, AS SIGNORS TO C. KLAUBERG & BROS. INC., OF NEW YORK, N. Y., A CORPORATION OF NEW YORK.

SAFETY RAZOR.

1,416,090.

Specification of Letters Patent. Patented May 16, 1922.

Application filed March 17, 1920. Serial No. 366,649.

To all whom it may concern:

Be it known that I, WILLIAM J. KLAUBERG, a citizen of the United States, and residing at No. 316 West 82nd Street, in 5 the city of New York, borough of Manhattan, county and State of New York, have invented certain new and useful Improvements in Safety Razors, and more particularly to that type of safety razor in which 10 some portion of the guard or blade covering elements has a contact with the face of the user during the operation of shaving.

The object of the invention is to provide means designed to have contact with the face 15 of the user whereby to guide the razor in a diagonal direction to produce what is technically known to those skilled in this art as an "angular stroke."

A further object of the invention is to 20 provide such a razor with guard teeth angularly disposed with relation to the line of the edge of the blade and extending preferably in the direction of movement of the razor when producing the so-called diagonal 25 or angular stroke.

With the foregoing objects in view the invention may be said to consist of a safety razor provided with means arranged to have contact with the face of the user whereby 30 to guide the razor and cause the same to move over the face of the user in a direction to produce a diagonal or angular stroke.

The invention further consists of a safety razor provided with guard teeth disposed 35 angularly with relation to the line of the cutting edge of the blade and preferably in the direction of the movement of the razor over the face of the user.

The invention further consists of the devices and combinations of devices herein- 40 after described and claimed and as shown in the accompanying drawings.

In the drawings I have shown my invention as embodied in a well-known and popular form of safety razor provided with a double-edged blade, but it is to be understood that my invention is not limited to such a form but is equally applicable to other forms of safety razors.

50 The invention is illustrated in the accompanying drawings in which—

Figure 1 shows in side elevation a safety razor embodying the present invention.

Figure 2 shows a face view of the razor shown in Figure 1 looking at the face of the 55 clamping plate.

Figure 3 shows a rear view of the bed plate, the handle being shown in cross-section.

Figure 4 shows a longitudinal sectional view 60 of the clamping plate taken on the line 4—4 in Figure 2.

Figure 5 shows a transverse sectional view 65 of the clamping plate taken on the line 5—5 in Figure 3.

Similar reference characters will be employed throughout the specification and drawings to indicate corresponding parts.

As shown in the drawings my invention is embodied in a safety razor comprising a 70 handle 1, a bed plate 2, a clamping plate 3, and a blade 4.

As is well understood by those familiar with this form of razor the clamping plate 3 is provided with a screw which passes 75 through the bed plate 2 and is engaged by threaded means carried by the handle 1, whereby the parts are separable, with the blade 4 clamped tightly between the bed plate 2 and the clamping plate 3, with the 80 edges of the blade at opposite sides extending beyond the edges of the clamping plate.

And also, it is well understood that when in operative condition this blade is curved transversely, and that by loosening or tightening the clamping means, the edges of the blade 85 may be adjusted for either a close shave or otherwise.

The bed plate 2 along its opposite edges is 90 provided with the guard teeth 5 which, as clearly shown in Figures 2 and 3, project out beyond the cutting edges of the blade 4. These guard teeth 5 are inclined as shown clearly in Figures 2 and 3 so that they project in an angular direction with relation 95 to the line of the cutting edge of the blade 4 and preferably the guard teeth 5 upon opposite edges will extend in the same direction or angular line.

By forming these guard teeth 5 so that 100 they are angularly disposed with relation to the cutting edge of the blade, the hair which is to be cut by the edge will be guided and caused to approach the edge in an inclined direction with relation to the cutting edge, 105 and as the edges of the guard teeth and the

edge of the blade form a more or less obtuse angle instead of a right angle, as is usual with razors of this character, the edge of the blade will not come into abrupt contact with the hair to be severed, but there will be more or less of a gradual and inclined relative movement between the edge of the blade and the hair to be severed.

The best result in the use of any razor is secured by imparting thereto what is generally known as an angular or diagonal stroke over the face of the user and it is to insure such a diagonal or angular stroke that I provide the outer face of the clamping plate 15 3 with parallel diagonally extending grooves 6 and ribs 7.

The grooves and ribs preferably extend over the entire surface of the clamping plate 3 and from edge to edge thereof, and 20 as shown in Figure 2 the grooves 6 are positioned so that they coincide with the opening 8 between the guard teeth 5, and the grooves and ribs in the surface of the guard plate extend in the same direction or are 25 disposed at the same angle with relation to a longitudinal line cutting the center of the razor, as for instance the line 4—4 in Figure 2.

As shown in Figure 4 the grooves 6 are 30 preferably concaved along the base line as shown at 9 and the walls of the grooves extend perpendicularly and form a relatively sharp angular shoulder with the upper surface of the ribs as indicated at 10.

35 By thus forming the ribs and grooves they will, when pressed against the face of the user, have a more or less frictional engagement therewith and as the skin will have a tendency to enter the grooves, the razor 40 when drawn over the face with the surface of the clamping plate 3 immediately adjacent to the cutting edge of the blade 4 in engagement with the face, will be guided in the direction of the ribs and grooves and thus 45 move over the face in a diagonal or angular direction producing the so much to be desired angular stroke.

It is of course to be understood that my 50 invention is not limited to the particular type of safety razor illustrated and described, but it can be adapted to any form of safety razor in which there is a plate or bearing which contacts with the face of

the user at a point adjacent to the cutting edge of the blade while making a shaving 55 stroke.

Having described my invention, I claim:

1. A safety razor comprising a bed plate and a clamping plate, the outer surface of the clamping plate being provided with parallel grooves and ribs positioned to engage the face of the user to guide the razor over the face.

2. A safety razor comprising a bed plate and a clamping plate, the outer surface of the clamping plate being provided with diagonally arranged parallel grooves and ribs positioned to engage the face of the user to guide the razor over the face.

3. A safety razor comprising a bed plate 70 having along one edge a plurality of projecting spaced guard teeth, and a clamping plate provided with parallel grooves and ribs upon its outer surface, the grooves coinciding with the spaces between the guard teeth of the 75 bed plate.

4. A safety razor comprising a bed plate and a clamping plate, the bed plate being provided with guard teeth along its edge and extending diagonally with relation to the 80 edge, and a clamping plate provided with parallel grooves and ribs upon its outer surface extending in a diagonal direction at an angle substantially that of the guard teeth of the bed plate.

5. A safety razor comprising a curved bed plate having along its opposite edges guard teeth projecting therefrom at an angle thereto, the teeth on the opposite edges being substantially in the same angular line, and a 90 curved clamping plate the outer face of which is provided with parallel ribs and grooves formed upon an angle corresponding to that of the guard teeth, and the grooves coinciding with the spaces between the 95 teeth.

6. A safety razor comprising a curved bed plate having along one edge thereof guard teeth projecting therefrom at an angle thereto, and a curved clamping plate provided 100 with parallel ribs and grooves formed upon an angle corresponding to that of the guard teeth, and the grooves coinciding with the spaces between the teeth.

WILLIAM J. KLAUBERG.
